DESIGN FOR A DRESS

John Casella, Long Beach, N. Y.

Application November 5, 1940, Serial No. 96,315

Term of patent 3½ years

To all whom it may concern:

Be it known that I, John Casella, a citizen of the United States, residing at 211 Laurelton Blvd., Long Beach, in the county of Nassau and State of New York, have invented a new, original, and ornamental Design for a Dress, of which the following is a specification, reference being had to the accompanying drawing, forming part thereof.

I claim:

The ornamental design for a dress, substantially as shown.

JOHN CASELLA.
